UNITED STATES PATENT OFFICE.

CHARLES V. FOULDS, OF BERKELEY, CALIFORNIA.

CARBURETER.

1,116,581.

Specification of Letters Patent Patented Nov. 10, 1914.

Application filed November 19, 1913. Serial No. 801,819.

To all whom it may concern:

Be it known that I, CHARLES V. FOULDS, a citizen of the United States, residing at Berkeley, in the county of Alameda and State of California, have invented certain new and useful Improvements in Carbureters, of which the following is a specification.

My invention relates to the class of carbureters.

It has for its object the efficient and practical regulation of the mixture of gasoline and air for internal combustion engines, throughout their entire range of operation, the requirements of a carbureter to attain this object being, first, that it shall supply a uniform mixture of minimum volume, for light running or "idling"; second, that it shall supply a uniform mixture of maximum volume with minimum resistance to the flow of air through it, for full load; and, third, that it shall supply a uniform mixture of constant proportion for every load between these two.

With this object in view, my invention consists in the novel carbureter which I shall hereinafter fully describe, by reference to the accompanying drawings in which—

Figure 1 is an elevation of my carbureter. Fig. 2 is a vertical section on the line $x-x$ of Fig. 1. Fig. 3 is a vertical section on the line $y-y$ of Fig. 2. Fig. 4 is a horizontal section on the line $z-z$ of Fig. 3.

The shell 1 of the carbureter has at one side of its foot the air inlet connection 2, and at its head the engine-intake connection 3. The middle portion of the shell is formed with opposing cylinders 4 which constitute the seats for the pistons 5. These cylindrical seats open into the throat of the shell by continuing walls which are so formed as to present, in the median line on each side, a seat at 6, seen best in Fig. 2, for an arc of the pistons, thereby enabling the pistons, where they project into the throat, to form a closure therein; and the walls of the throat, from this arc seat 6, both above and below, are flared upward and downward respectively, to present elliptical throat spaces 7, as are seen partially in Fig. 2, and are fully indicated by the dotted lines in Figs. 3 and 4. The pistons 5 project into these throat spaces 7 from opposite sides. The inner ends of the pistons are so shaped or cut out, as shown at

5' in Figs. 2 and 3, as to form between them, when brought together, an hour-glass opening or oppositely flaring passage, as clearly shown in Fig. 3, which opening or passage 60 has come to be known in the art as a Venturi tube; and this shape of the piston ends so coacts with the flaring elliptical throat-openings 7 of the shell, that as said pistons separate or approach, the general Venturi 65 tube shape of the throat passage which the pistons thus control and vary, is preserved for any piston position, such shape being known to be good practice and form for a passage surrounding an aspirating nozzle. 70

Each piston 5 is controlled by a spring 4' seated in a socket in its outer portion and bearing against an end cap 8 of the seat 4, said springs acting to move the pistons toward each other. The pistons are separated by means of pins 9 secured in the side of each, said pins playing in slots 10 in the piston-seats 4, and carrying on their outer ends the rollers 11. Between these rollers, as seen in Fig. 1, operates a cam 12, which 80 is mounted and guided on the exterior of the shell by means of lower studs 13, and an upper stud 14 over which the cam 12 plays by a slot 15.

In the passage in the head of the shell 85 leading to the engine-intake is mounted the usual butterfly valve or "throttle" 16 with the pivotal pin 17 of which suitable operating connections, not necessary herein to show, are to be made. The pivotal pin 17 90 of the throttle carries a crank 18 from which a connecting link 19, shown in Figs. 1 and 2, extends to and is connected with the cam 12 at 19'. Thus the pistons 5 are mechanically connected with and are dependent for their 95 operation upon and in accordance with the operation of the throttle. I do not, however, confine myself to the particular connections here illustrated, for others may be employed, though in these connections as described there is involved a special feature, namely, the employment of a cam, the shape of which can be easily changed to vary and initially determine the piston movement and control as required by different engines 100 and different sizes of engines. 105

20 is the aspirating nozzle, the outlet of which lies in the horizontal middle plane of the Venturi-throat of the shell between the controlling pistons. This nozzle may be 110 mounted in any suitable manner. I have here shown it as carried in the upper arm

- of a nozzle-chamber T-fitting 21, the lower arm of the fitting being connected by a nipple 22 with a tube-standard 23 rising from the foot of the shell 1. The nozzle 20 is fitted with a needle valve 24, the stem 25 of which is carried by and adjustable in packing 26 in the tube-standard 23. The connections to operate the needle valve need not be here shown.
- 10 27 is the float-chamber, having a gasolene connection at 28 controlled in the usual manner by a valve 29 operated by the float 30. The float-chamber 28 is carried by the shell 1 and communicates with the aspirating nozzle 20 by suitable connections, here shown as consisting of a nipple 31, joining the float-chamber with the nozzle-chamber fitting 21.
- 15 32, in Fig. 2, is a vertical tube, which at its lower end opens into the lower portion of the float-chamber 27, as indicated at 33. The tube 32 rises to the level of the top of the shell 1, which level is, in practice, about two inches above the normal level of the 20 gasolene in the float-chamber. The top of the tube 32 is connected by a small tube 34 with the upper portion of the shell 1 above the throttle 16, and said small tube opens into the shell at this point, as indicated at 25 35. The small tube 34 is fitted with a needle regulating valve 36, and the tube 32 has a small hole 37 in its top, open to the atmosphere.
- 20 From the foregoing description of the construction of the carbureter, the following deductions bearing on its operation may be drawn. The air passage or throat of the carbureter is varied by the movement of the controlling pistons 5, and the operation of 25 these pistons being dependent on the operation of the throttle 16, it follows that for any given position of the throttle, there is a definite position of the pistons, and, consequently, a definite cross-section area for the 30 throat. Within certain limits, the amount of liquid drawn from an aspirating nozzle varies directly with the speed of the gas passing the nozzle. Now, assuming the throttle to be at some fixed position, and, 35 consequently, admitting a fixed quantity of gas to the engine, the quality, that is, the proportion of gasolene vapor to air, will depend on the area of the throat surrounding the nozzle, since the quantity of gas remains 40 the same, while the speed by the nozzle and with it the amount of vapor drawn out, depends on the area of the throat, which as here shown is regulated by the position of the pistons. Therefore, with any position of 45 the throttle and size of aperture in the nozzle, the correct mixture may be had by adjusting the positions of the pistons. By this means is attained the proper mixture for any constant condition of operation. The 50 function of the vertical tube 32 may now be

explained. Under varying conditions, that is, with sudden changes of throttle opening another factor enters and must be provided for. At small throttle, with high vacuum in the intake pipe, the interior of this pipe is fairly dry; but at large throttle, with low vacuum, the interior of the pipe is coated with a thin film of the liquid fuel. When, therefore, the throttle is suddenly opened, this film must be first deposited before the 70 normal operation, at that throttle opening, may commence. At small throttle, with high vacuum, the needle-valve 36 is regulated to permit enough air to rush through the small tube 34 into the intake pipe, to reduce the pressure in the vertical tube 32, until a column of gasolene is raised therein from the float chamber to a height just below said small tube. When the throttle is opened, the pressure in the intake pipe rises, 75 and, consequently, the amount of air going into the small tube becomes less, so that the column of gasolene falls. This causes a temporary rise in the level of gasolene in the float-chamber and forces a little extra fuel 80 out of the nozzle to form the needed film.

I claim:—

1. In a carbureter, the combination of a shell having an air inlet, an outlet to the engine-intake, and an intervening throat-opening; an aspirating nozzle fitted in the throat-opening; a throttle controlling the outlet to the engine intake; opposingly reciprocating pistons seated in the shell with their inner ends projecting into the throat-opening thereof, and adapted by their approach and recession to vary the cross-sectional area of said throat-opening; and means for operating the pistons from and conformably with the operation of the throttle, consisting of a cam, connections between the cam and the pistons, and connections between the throttle and the cam. 100
2. In a carbureter, the combination of a shell having an air inlet, an outlet to the engine-intake, and an intervening throat-opening; an aspirating nozzle fitted in the throat-opening; a throttle controlling the outlet to the engine-intake; and opposingly reciprocating pistons mounted in the shell and projecting into the throat-opening thereof, the inner ends of the pistons being cut out to form between them an oppositely flaring passage surrounding the aspirating nozzle, said passage being 110 variable by the approach and recession of said ends.
3. In a carbureter, the combination of a shell having an air inlet, an outlet to the engine-intake, and an intervening throat-opening; an aspirating nozzle fitted in the throat-opening; a throttle controlling the outlet to the engine-intake; opposingly reciprocating pistons mounted in the shell and projecting into the throat- 115 120 125 130

- opening thereof, the inner ends of the pistons being cut out to form between them an oppositely flaring passage surrounding the aspirating nozzle, said passage being 5 variable by the approach and recession of said ends; and means operated by the throttle movement to reciprocate said pistons conformably therewith.
4. In a carbureter, the combination of a shell having an air inlet, an outlet to the engine-intake, and an intervening throat-opening, said opening having walls shaped to form interior spaces flaring both up and down from a median plane; an aspirating nozzle fitted in the throat-opening; a throttle controlling the outlet to the engine-intake; opposing, oppositely reciprocative pistons mounted in the shell and projecting into the throat-opening thereof to 10 form a closure in its median plane, the inner ends of the pistons being shaped to form when together an oppositely flaring passage and to continue during their recession, the general shape of said passage 15 in conjunction with the flaring interior spaces of the throat-opening of the shell; and means for reciprocating said pistons to vary the cross-sectional area of said throat-opening.
- 20 5. In a carbureter, the combination of a shell having an air inlet, an outlet to the engine-intake, and an intervening throat-opening, said opening having walls shaped to form interior spaces flaring both up and 25 down from a median plane; an aspirating nozzle fitted in the throat-opening; a throttle controlling the outlet to the engine-intake; opposing, oppositely reciprocative pistons mounted in the shell and projecting 30 into the throat-opening thereof to form a closure in its median plane, the inner ends of the pistons being shaped to form when 35 together an oppositely flaring passage and to continue during their recession, the general 40 shape of said passage in conjunction with the flaring interior spaces of the 45
- throat-opening of the shell; and means operated by the movement of the throttle to reciprocate said pistons to vary the cross-sectional area of the throat-opening conformably with said throttle movement. 50
6. In a carbureter, the combination of a shell having an air inlet, an outlet to the engine-intake, and an intervening throat-opening; a throttle controlling the outlet to the engine-intake; an aspirating nozzle fitted in the throat-opening; a float-chamber connected with the aspirating nozzle; a vertical tube leading out from the lower portion of the float chamber and rising above said chamber, said tube having an air inlet in its upper end; a tube connecting the upper end of the vertical tube with the shell at a point above the throttle; and a valve to regulate the passage of air through the connecting tube. 55
7. In a carbureter, the combination of a shell having an air inlet, an outlet to the engine-intake, and an intervening throat-opening; a throttle controlling the outlet to the engine-intake; an aspirating nozzle fitted in the throat-opening; means operated by the throttle movement and in conformity therewith for varying the capacity of the throat-opening; a float-chamber connected with the aspirating nozzle; a vertical tube leading out from the lower portion of the float chamber and rising above said chamber, said tube having an air inlet in its upper end; a tube connecting the upper end of the vertical tube with the shell at a point above the throttle; and a valve to regulate the passage of air through the connecting tube. 60
- In testimony whereof I have signed my name to this specification in the presence of two subscribing witnesses. 65
